Stanley Curtis, Holland, Mich., assignor to Holland Furnace Company, Holland, Mich., a corporation of Delaware

Application December 23, 1944, Serial No. 117,043

Term of patent 14 years

(Cl. D81—21)

To all whom it may concern:

Be it known that I, Stanley Curtis, a citizen of the United States, residing at Holland, county of Ottawa, State of Michigan, have invented a new, original, and ornamental Design for a Register Grille or the like, of which the following is a specification, reference being had to the accompanying drawing forming a part thereof.

In the drawing:

Fig. 1 is a face view of a register grille or the like embodying my new design.

Fig. 2 is a sectional view taken as indicated at line 2—2 on Fig. 1.

I claim:

The ornamental design for a register grille or the like, substantially as shown.

STANLEY CURTIS.
